UNITED STATES PATENT OFFICE.

PAUL LOUIS MERGIER AND HENRI EMILE GUIBERTEAU, OF PARIS, FRANCE.

DEVICE FOR THE GRAPHIC REPRESENTATION OF FUNCTIONS.

Application filed June 4, 1923, Serial No. 643,471.

To all whom it may concern:

Be it known that we, PAUL LOUIS MERGIER and HENRI EMILE GUIBERTEAU, citizens of the French Republic, both residing at Paris, France, have invented new and useful Improvements in a Device for the Graphic Representation of Functions, of which the following is the specification.

This invention relates to a device for the graphic representation of functions.

Up to now, the graphic representation of the functions was made by tracing on a sheet of paper or a board suitably divided for permitting the rapid measurement of the coordinates. This system has several inconveniences: in case the board is vertically arranged, against a wall for instance, the tracing is relatively difficult and, on the other hand, any error necessitates erasure which spoils the correct tracings already executed at the same place. On the other hand, as the diagrams are often used for laying out a rather large number of different curves, it was necessary to employ inks of various colors; now, it is difficult, after a certain interval of time of obtaining inks of rigorously similar colors, or the colors of which modify in the same manner by exposure to the air.

The device forming the subject matter of the invention permits the tracing of the graphic representations of functions by means of material lines (textile threads or bands, wires or metallic bands) connecting the points of each curve which have been previously determined.

This device has therefore the following advantages:

1. It does not necessitate the use of any tracing member proper, thus avoiding the danger of spots, for instance and permits the arrangement of diagrams in any position.

2. Any error made is easily repaired by displacement of the material line, without leaving trace of the correction and without damaging the tracings already executed.

3. It is possible to do away with a curve of a diagram, by removing the material line constituting the same, without damaging the other tracings.

4. The same board can be used indefinitely.

The device forming the subject matter of this invention is essentially characterized in that it is constituted by several combs separated by bars, the teeth of the combs extending beyond the bars, the latter serving more-

over to secure the combs on a plane support, in the manner more fully indicated hereafter. The threads or wires which serve to represent the curves are hooked between two successive teeth of the combs, so as to pass in the recess the ordinate of which corresponds to that of the point through which the curve must pass.

In order that the invention may be clearly understood, a form for carrying it out has been illustrated in the accompanying drawing in which:

Fig. 1 illustrates a comb which can be used as previously indicated.

Figs. 2 and 3 illustrate modifications.

Fig. 4 is a plan view of the diagram obtained:

Fig. 5 is a section according to line A—A.

Fig. 6 is a section according to line B—B.

Fig. 7 is a section according to line C—C.

The combs 1 are mounted in the following manner on a small plane rectangular board 10 (Figs. 5 and 6). On two opposed edges of this board 10 are secured, by means of screws 11 and 11', small strips 12 and 12', cut away at 13 and 13' for forming slides (Fig. 6). The combs 1 are adjustable between the small strips 12 and 12' and at right angles to the same, and moreover they are separated by small bars 3 sliding in the slides 13 and 13', the shape of which is for instance that of a rabbet. The end bars 4 and 4' are secured to member 10 by means of screws 5 and 5' so that the clamping of the combs 1 between the small sticks is sufficient for immobilizing the whole structure.

The small bars 3, 4 and 4' are provided with graduations 6 facilitating the reading. The teeth of the combs can also be regularly colored in agreement with the graduations of the said bars 3.

These bars 3 which determine the spacing apart of the combs may be of the same width or of different widths.

A diagram with Cartesian coordinates has been shown in Fig. 4 the curves being constituted by the threads or wires 7.

The small bars 3, 4, 4' and 12' are preferably plated with celluloid or other similar materials, so as to be able to trace any notes, signs or reference marks.

The wires or threads 7, which represent the curves, must be fitted between the teeth of the combs. The recesses 2 between the teeth can be rectilinear, as shown in Fig. 1, or they can be wider at the base than to-

wards their middle portion (Fig. 2) or towards their top (Fig. 3). These two latter arrangements permit of introducing the thread or wire at the bottom of the recesses, owing to the resiliency of the teeth, but prevent the accidental escape of the said thread or wire.

The threads or wires are each held at one of their ends by a bead 13, the diameter of which is greater than the distance separating two teeth of a comb. At the other end, the threads or wires 7 are provided with counterweights 8, ensuring their tension, and on which are secured plugs indicating which function is represented by the particular thread or wire. The threads or wires can also be mounted for ensuring their tension on a winding device composed of a small pulley 9 the axis of which is constituted by a screw 14 secured in the small board 10.

It is also possible to provide protecting devices for the diagrams obtained. Each comb can be, for instance, covered by a cap 15, which prevents the thread or wire from escaping from the teeth.

What we claim as our invention and desire to secure by Letters Patent is:—

1. In a device for the graphic representation of functions, a plane support, bars resting on the support, a plurality of combs, each interposed between two successive bars, the teeth of the combs projecting above the bars, means for securing the bars and the combs on the support, threads for passing between the teeth of the combs, means for securing the threads at one of their ends to one of the combs, and means for maintaining the threads in a stretched condition.

2. In a device for the graphic representation of functions, a plane rectangular support, two strips secured to the support and parallel to two opposed edges of the same, a plurality of bars resting on the support and between the two strips, combs interposed each between two successive bars, the teeth of the combs projecting beyond the bars, means for securing the bars and the combs on the support, threads for passing between the teeth of the combs, means for securing the threads at one of their ends to one of the combs, and means for holding the threads in a stretched condition.

3. In a device for the graphic representation of functions, a plane rectangular support, two strips secured to the support, and parallel to two opposed edges of the same, the strips being cut away to form slideways, bars resting on the support between the two strips and at right angles thereto, and slideable in the slideways, combs, each interposed between two successive bars, the teeth of the combs extending beyond the bars, screws securing the end bars to the support, threads passing between the teeth of the combs, means securing these threads at one of their ends to one of the combs, and means holding these threads in a stretched condition.

4. In a device for the graphic representation of functions, a plane rectangular support, two strips secured on the support and parallel to two opposed edges of the same and cut away for forming slideways, bars resting on the support between the two strips and at right angles thereto, and slideable in the slideways, combs, each interposed between two successive bars, the teeth of the combs extending beyond the bars, screws securing the end bars to the support, threads passing between the teeth of the combs, a bead secured at the end of each thread and of greater diameter than the teeth gaps, and means for holding the threads in a stretched condition.

5. In a device for the graphic representation of functions, a plane rectangular support, two strips secured on the support and parallel to two opposed edges thereof, and cut away for forming slideways, bars resting on the support between the two strips and at right angles thereto, and slideable in the slideways, combs, each interposed between two successive bars, the teeth of the combs extending beyond the bars, screws securing the end bars to the support, threads passing between the teeth of the combs, a bead secured at the end of each thread, and of greater diameter than the distance separating two teeth, and pulleys mounted on the support and receiving the other ends of the threads.

In testimony whereof we have signed our names to this specification.

PAUL LOUIS MERGIER.

HENRI EMILE GUIBERTEAU.
